DISPENSING PACKAGE FOR LIQUIDS

Ralph W. Wilson, New York, and Brent F. Cahoon, Forest Hills, N. Y., assignors to Captive Closures, Inc., New York, N. Y., a corporation of Delaware

Application April 1, 1937, Serial No. 134,206

19 Claims. (Cl. 221—147)

This invention relates to dispensing packages for liquids.

In an application filed September 16, 1936, Serial No. 101,046, Patent No. 2,117,296, applicant 5 Cahoon has disclosed several different forms of a dispensing package in which the liquid is ejected by a pumping action.

It is an object of the present invention to provide a dispensing package of the general type 10 closed in said application 101,046, in which certain of the parts are of a more simple construction and capable of more economical production.

With this and other objects in view the invention consists in the features, combinations, details of construction and arrangement of parts 15 which will first be described in connection with the accompanying drawings and then more particularly pointed out.

In the drawings,—

20 Figure 1 is a vertical sectional view of a package, including container and cap, constructed in accordance with the present invention, showing the cap closed;

25 Figure 2 is a similar view showing the cap open and the container inverted for dispensing;

Figure 3 is a sectional view (enlarged) taken on the line 3—3 of Figure 1;

Figure 4 is a plan view (enlarged) of one of the parts;

30 Figure 5 is a vertical sectional view (enlarged) of a modified check valve;

Figure 6 is a similar view of a further modification of a check valve;

Figure 7 is a top plan view of the check valve 35 unit of Figure 6;

Figures 8 and 9 are views similar to Figures 1 and 2, illustrating a modified form of package, and

40 Figures 10 and 11 are similar views illustrating a further modification.

Referring to the drawings, the embodiment illustrated as an example in Figures 1 and 2 comprises a container in the form of a glass bottle or flask 11 having a neck 12. Associated with this 45 container, in forming the complete package, is a cap 14 having a skirt 15 which telescopes over the bottle neck. This cap may conveniently be formed of molded plastic material.

There is provided means for releasably locking 50 or holding the cap in closed position. To this end, as here shown as an example, near the base of the bottle neck is a short external thread 16 engaged by a complementary thread 17 on the interior of the cap skirt and near the bottom 55 thereof.

In this connection, it is noted that although the package will ordinarily be inverted for dispensing, the terms "top", "bottom", "up", "down" and the like, will be used herein as referring to the upright position of the container unless otherwise specified. 5

According to the invention in its entirety, the cap, upon disengagement of the threads, becomes a pumping element. To this end, there is provided means whereby the cap is capable of a limited axial reciprocation with respect to the bottle neck when the threads 16, 17 are disengaged. In the present exemplification, carried by the bottle neck, as later described, is an outwardly and downwardly extending locking or limiting flange 18 located not far below the bottle mouth. Just above the cap thread 17 is an internal stop shoulder 19 arranged to engage flange 18 upon upward movement of the cap, to limit such movement and lock the cap against removal. 20

The flange 18 and shoulder 19 may conveniently be constructed and assembled as described in said application Serial No. 101,046. As there shown and described, the flange is substantially circular and the co-operating shoulder is so formed that the inner edge defines an oval or ellipse. The major axis of this oval is somewhat greater than the diameter of the lower, contacting edge of the flange and the minor axis is somewhat less than such diameter. In assembling the parts, flange and shoulder are brought into contact and application of the necessary force or pressure causes the somewhat yieldable metal flange to be deformed to oval shape. As this oval is slightly smaller than the oval defined by the shoulder, the shoulder can pass the flange. Thereupon, the flange returns to circular form by virtue of its inherent resiliency and thereafter the shoulder underlies the flange in the manner here shown. In referring to circles and ovals, it 30 is to be understood that the same may be continuous or interrupted. 35

An alternative construction, also described and shown in said application permits the use of a circular shoulder. In this case, the flange is 40 slotted and can contract sufficiently to pass the shoulder.

Upon disengagement of the threads, the cap is free to be reciprocated, its range of movement being fixed in one direction by the engagement 50 of shoulder 19 with flange 18 and in the other direction by the contact of threads 16, 17 which thus serve as stops.

For convenience of description, the position of the cap when screwed down on the bottle thread, 55

as illustrated in Figure 1, will be referred to as the "closed" position and the position of the cap when displaced axially until shoulder 19 engages flange 18, as illustrated in Figure 2, will be referred to as the "open" position.

There is provided means for tending to keep the cap in open position when the threads 16, 17 are disengaged. To this end, as here shown as an example, a coiled spring 20 is confined between flange 18 and the top wall of the cap. As soon as the threads are disengaged, spring 20 moves the cap to the open position of Figure 2.

The invention in its entirety includes a barrel, in the nature of a pump barrel, carried by the container and a pump plunger operated by the cap. Although capable of various constructions, in that shown as an example in Figures 1 and 2, extending down into the bottle neck and supported therefrom as later described, is a metal barrel 23. Reciprocable in this barrel is a pump plunger 24. In the present exemplification, an operative connection between plunger and cap is effected by making the plunger an integral part of the cap. The plunger 24 has a central bore 25 communicating with a central bore or port 26 in the top of the cap, bore 25 and port 26 constituting a discharge passage for the container contents.

In the bottom wall 27 of the barrel is a centrally located inlet port 28 for passage of the container contents to the pump chamber.

The invention in its entirety includes means for controlling the inlet port and for closing the discharge passage. This may conveniently be accomplished by a floating valve element for controlling the inlet port and having a portion for closing the discharge passage when the cap is closed. To this end, in the embodiment shown as an example in Figures 1 and 2, in the lower end 40 of the barrel, and floating therein, is a combined valve element comprising a hollow plug portion 30 having a frusto-conical top adapted to make sealing engagement with a tapered valve seat 31 formed at the mouth of bore 25. Extending outwardly from the base of plug 30 is a flange 32 which normally seats on the barrel bottom 27. At the juncture of plug and flange, the valve element has an annular dished portion in the nature of a bead 33 which extends into the port 28. The flange 32 is provided with a plurality of cutouts 34 (Figure 3) for the passage of liquid when the flange 32 lifts from its seat.

Movement of the floating valve element 30-32 is limited in one direction by its engagement with the bottom of the barrel and in the other direction by the engagement of flange 32 with a bead 35 struck in from the wall of the barrel and which may be continuous or interrupted.

The invention in its entirety includes a floating check valve for the discharge passage. To this end, in the exemplification shown in Figures 1 and 2, secured in the top of plunger bore 25 with a friction fit is a cup-shaped element 40 having an opening 41 in its bottom wall. The latter 65 thus serves as a ported partition in the discharge passage. Floating in cup 40 is a check valve comprising a flat valve disk 42 which normally seats on the bottom of the cup to close the discharge passage. Extending upwardly from disk 42 are a plurality of lugs 43 which engage the wall of cup 40 to guide the valve element in its movement. Movement of this check valve is limited in one direction by its engagement with the bottom of cup 40 and in the other direction by the engagement of lugs 43 with a bead 44 struck in from

the wall of the cup and which may be continuous or interrupted. The disk 42 is provided with a plurality of cutouts 45 (Figure 4) for the passage of liquid when the check valve lifts from its seat.

While the locking flange 18 and the pump barrel may be associated with and supported from the bottle in various ways, they may conveniently be parts of an attachment unit permanently secured to the bottle neck. To this end, as shown as an example in Figures 1 and 2, the attachment unit includes a metal clamp ring 51 which embraces the mouth of the bottle. This ring has an inwardly extending V-shaped bend or bead 52 which locks under a shoulder 53 formed by a so-called lock ring 54 at the bottle mouth. This lock ring is similar to the lock ring provided on bottles sealed by closures of the crown cork type. The locking flange 18 is formed as an extension of one leg of the V-shaped bend 52. The clamp ring 51 also has an inturned clamping flange 55 which takes over the lip of the bottle. The pump barrel 23 is suspended by means of an outwardly extending supporting flange 56 clamped between clamp flange 55 and the bottle lip.

Clamped between supporting flange 56 and clamp flange 55 is a compressible gasket 57 of cork, felt or other suitable material. This gasket serves to prevent leakage from the barrel and its inner edge makes wiping contact with plunger 24 so that it serves as a pump packing.

Compressed between flange 56 and the bottle lip is a second gasket 58 which serves to prevent leakage from the container up over the bottle lip.

This attachment unit may be constructed and assembled with the bottle in various ways, for example, as described in said application Serial No. 101,046. As there shown and described, the V-shaped bend of the attachment unit is substantially circular and the bottle neck is so formed that the bottle locking ring is oval or elliptical in outline. The major axis of this oval is slightly greater than the diameter of the apex of the V-shaped bend and the minor axis is somewhat less than such diameter. In assembling the attachment with the bottle, V-shaped bend and lock ring are brought together and application of the necessary force or pressure causes the somewhat resilient metal of the attachment to be deformed to oval shape. As this oval is slightly larger than the oval of the bottle lock ring, the bend can pass the ring. Thereupon, the bend returns to circular form by virtue of its inherent resiliency and snaps under the bottle shoulder.

Other constructions are, of course, possible. As further described and shown in said application Serial No. 101,046, the V-shaped bend may be formed during assembly by a spinning operation. In that case the bottle locking ring may be circular. Or, the shoulder and bend both being circular, the V-shaped bend may be slotted, thus permitting the bend to expand sufficiently to pass the locking ring. In referring to circles and ovals, it is to be understood that the same may be continuous or interrupted.

Once the parts are assembled, the combined gripping action of bead 52 and clamp flange 55 securely clamps the attachment unit to the container with the pump barrel suspended in the container mouth.

Figure 1 shows the package closed for shipment, storage and when not in use. In this position, the combined valve element 30-32 is pressed downwardly by the plunger 24 with valve flange 32 engaging barrel bottom 27. This provides a double seal. The engagement of flange 75

32 with the barrel bottom, with bead 33 engaging the rim of the inlet port, prevents leakage of liquid from the container into the pump barrel. The engagement of plug 30 with valve seat

5 31 prevents leakage into the discharge passage of any liquid that may remain in the barrel or that may, by chance, work its way into the latter.

Leakage from the barrel to the outside is prevented by gasket 57 and leakage from the container over the bottle mouth is prevented by gasket 58.

When it is desired to obtain an application of the hand lotion or other contents, the cap is unscrewed until the threads 16, 17 disengage, thus 15 freeing the cap which thereupon becomes a pump actuating element. So freed, the cap is moved away from the bottle, by spring 20, until shoulder 19 engages flange 18. During this opening movement, valve seat 31 moves away from plug 20 30, thus opening the discharge passage at that point and freeing the valve element 30-32 to permit the latter to float.

It will be apparent that to dispense the contents, the bottle must be inverted. Whether the 25 cap is opened before or after inversion is immaterial. If before, the initial opening stroke will ordinarily be an idle one and one or more reciprocations of the cap, in the nature of "priming" strokes, will be necessary after inversion. If the 30 cap is opened after inverting the bottle, such priming may be found necessary. For the purposes of the present description, it will be assumed that the cap is unscrewed after the bottle is inverted (Figure 2) and that no priming stroke 35 is involved.

The movement of the cap to open position and the consequent movement of plunger 24 may be termed the suction stroke of the pump unit. During this stroke, the force of the air which 40 tends to flow into the pump chamber through port 26 causes check valve 42 to seat, thus closing the passage against the entrance of air. Whether the inlet control valve 30-32 opens by gravity when the bottle is first inverted or by 45 gravity or suction or both during the suction stroke is immaterial. In any event, such valve opens at some stage prior to the end of the suction stroke, permitting a flow of liquid into the pump chamber, such flow being the result of 50 gravity, suction or both.

The dispensing operation may be carried out in various ways. For example, the bottle may be held in one hand and the pump-actuating cap reciprocated by a finger of that hand. Or the 55 cap may be actuated by the palm of the other hand. In any event, the cap is moved toward the container until the threads 16, 17 come into contact to limit such movement. This is the compression or expelling stroke of the pump. As a 60 result of this stroke, inlet control valve 30-32 is forced against its seat to close the inlet; check valve 42 is forced open, unless it has previously opened by gravity; and a charge of liquid is forced out through discharge passage 25-26 in 65 the form of a jet. As only a small quantity is delivered on each force stroke, the user may give the pump-actuating cap several rapid reciprocations. Each suction stroke causes or permits the intake of a charge and each force stroke ejects a 70 charge.

After use, the bottle is returned to upright position and the cap closed. While no particular order is necessary, closing of the cap after the bottle is inverted is considered preferable. To 75 close the cap, it is axially moved toward the bot-

tle until the threads make contact and then rotated to cause the threads to mesh. As the cap is screwed down tight, the end of plunger 24 contacts plug 30 and rides valve element 30-32 down, unless the valve has previously seated 5 under gravity. In any event, the final tightening movement causes valve seat 31 to be pressed tightly against plug 30 and valve 30-32 to be pressed tightly against its seat, thus re-effecting the double seal previously described.

Instead of having the bottle held in the hand, it may be supported in a permanently inverted position. In case the supporting holder grips the cap, the relative rotary movement to disengage the threads and the relative axial movement 15 for pumping are effected by moving the bottle instead of the cap.

Figure 5 shows a modification of the check valve. The cup-shaped insert 40 is the same as above described. The check valve floating 20 therein, instead of having a flat disk, has an annular portion 60 which seats on the bottom of the cup and a conical portion 61 which plugs port 41.

Figures 6 and 7 illustrate a further modification 25 of the check valve. As there shown as an example, secured in the top of plunger bore 25 with a friction fit is a cup-shaped element 65 having an opening 65' in its bottom wall. The latter thus serves as a ported partition in the 30 discharge passage. Confined within cup 65 to control the passage is a check valve comprising a cup-shaped valve element 66 made of rubber or other suitable resilient material. The bottom of the rubber cup is domed upwardly and the top 35 of the dome is slotted as, for example, by cross slits 67 such as shown in Figure 7.

The shape of the dome tends to hold the slits closed. Upon the suction stroke, the pressure of the air inwardly against the dome tends to flatten the latter and close the slits more tightly. This closes the discharge passage and prevents 40 entrance of air. On the force stroke, the pressure of the liquid against the underside of the rubber valve element tends to extend the dome, 45 thus separating or opening slits 67 for the passage of the liquid.

In the modification of Figures 8 and 9, the attachment unit, which carries the pump barrel, comprises a metal skirt 70 having an internal 50 broken thread 71 which engages an external broken thread 72 on the neck 73 of bottle 74. Extending inwardly from skirt 70 is a flange 75. Between this flange and the lip of the bottle is a compressible gasket 76 of cork, pulp board or 55 other suitable material.

Forming part of the attachment unit is a pump barrel 77 extending down into the bottle neck. This barrel has an enlarged upper portion 78, the difference in diameter providing a ledge 60 or shoulder 79. At the top of this enlarged portion is an outwardly extending flange 80 confined between flange 75 and gasket 76, whereby the barrel is suspended in the bottle. When the attachment unit is assembled on the bottle, the 65 tightening of the screw-thread engagement causes gasket 76 to be compressed, thereby to prevent leakage from the bottle over the bottle lip.

Seated on ledge 79 and compressed by the 70 down-turned rim of flange 75 is a gasket 81 of felt, rubber or other suitable material. This gasket prevents leakage from the pump barrel and its inner edge makes wiping contact with the 75

pump plunger, thereby serving as a pump packing.

Telescoping over the skirt 70 of the attachment unit is a metal cap having a skirt 84 and a top portion 85, the latter having a central opening. The pump plunger of the embodiment under consideration is not integral with the cap but is associated therewith to form an operating unit. To this end, the pump plunger comprises a head 86 having a recess 87; a stem 88 of less diameter than the barrel; and a piston-like portion 89 having a running fit in the barrel. Passing through the central opening of the cap and wedged into recess 87 is a headed thimble 90 having a port or passage 91. The head of this thimble engages the top of the cap and its friction fit in the head of the plunger unites cap, thimble and plunger as an operating unit.

The pump plunger has a central bore 92. This bore, recess 87 and port 91 constitute a discharge passage for the container contents.

In the bottom of the barrel 71 is an inlet port 93 for the passage of the container contents to the barrel. This inlet port is controlled and the discharge passage is normally closed by a floating valve element 94 which is like the corresponding element of Figures 1 and 2 except that the plug portion 95 is dome shaped. A bead 96, struck in from the metal of the barrel and which may be continuous or interrupted, serves to limit upward movement of the floating valve element 94-95.

In the recess 87 is a floating check valve comprising a flat disk 97 and upstanding lugs 98 and having cutouts like those of valve 42 for the passage of liquid. This valve normally seats on the bottom of the recess and its upward movement is limited by the engagement of lugs 98 with thimble 90.

There is provided means for releasably locking the cap in closed position. Although capable of various constructions, as shown as an example in Figures 8 and 9, formed in the upper edge of skirt 70 of the attachment unit and located in diametrically opposed points, are two bayonet grooves 100. Struck inwardly from the metal of the cap skirt 84 are two similarly opposed nibs 101. To lock the cap in closed position, it is given an axial movement to bring nibs 101 into engagement with the rim of the skirt 70 and then an angular movement, if necessary, to bring the nibs in alignment with the vertical portion of the bayonet grooves 100. A further slight axial movement and a further slight angular or twisting movement cause the nibs to pass into the longitudinal portions of the bayonet grooves, thereby locking the cap. To open the cap, it is twisted slightly to bring nibs 101 into line with the vertical portions of the bayonet grooves, whereupon the cap is automatically raised to open position by virtue of a coiled spring 104 located between flange 75 and the top of the cap.

In the present exemplification, the opening movement of the cap is limited and its removal prevented by the engagement of the piston-like portion 89 of the pump plunger with gasket 81.

The invention in its entirety includes means whereby air may reach the interior of the bottle as the liquid contents are discharged. Although capable of various constructions, in that shown as an example in Figures 8 and 9, there is a substantial clearance between the stem 88 of the pump plunger and the wall of the barrel 71. Formed in the latter are a plurality of ports or holes 103, located just below ledge 79. It is believed that upon the force stroke of the pump

plunger, air is drawn into the space between the pump stem and the barrel, presumably entering between the pump plunger and gasket 81. This air can then flow, or upon the next suction stroke is forced, out through ports 103 into the bottle. Whether or not this is the true explanation, the fact remains that when ports 103 are provided the flow of air is visually demonstrated and the pump operates satisfactorily, whereas without such ports the construction of Figures 8 and 9 does not operate satisfactorily on thicker liquids.

Figure 8 shows the package closed. In this position valve element 94-95 provides a double seal as in the construction previously described. Upon a twisting movement of the cap to free the bayonet lock, the cap becomes a pumping element. So freed, the cap is moved to the open position of Figure 9 by spring 104. Assuming that the bottle has been inverted, this opening movement constitutes the suction stroke of the pump. During the opening movement, the valve seat formed by the mouth of bore 93 moves away from plug 95, thus opening the discharge passage at that point and freeing valve element 94-95 to permit the latter to float. By gravity or suction or both, valve 94-95 moves away from its seat. Thereupon, liquid from the bottle flows by gravity or suction or both into the pump barrel. Meanwhile, the force of air tending to flow into the pump chamber through port 91 causes check valve 97 to shut. It will be seen from Figure 9 that the piston-like portion 89 of the pump plunger prevents any flow of liquid through ports 103.

Reverse movement of the cap constitutes the expelling stroke. As a result of this stroke, inlet control valve 94-95 is forced closed; check valve 97-93 is forced open, unless it has previously opened by gravity; and a charge of liquid is forced out through the discharge passage.

The pumping stroke is limited in one direction by the engagement of piston 89 with gasket 81 and in the other direction by the engagement of nibs 101 with the rim of skirt 70. Should the nibs 101 happen to align with the bayonet grooves 100, the force stroke will be slightly longer because the nibs will later enter the vertical part of the grooves but this difference is immaterial so far as the operation is concerned.

After dispensing, the cap is closed as above described. During the latter part of the axial inward movement of the cap the end of the pump plunger contacts plug 95 and rides valve element down to seated position, unless it has previously seated under gravity, and the final closing movement effects a tight seal between plug 95 and the valve seat in the mouth of bore 92.

To assemble the parts, the attachment unit and cap are assembled together in any suitable manner and the combined assembly is assembled with the bottle simply by screwing the attachment unit down on the bottle thread.

Figures 10 and 11 illustrate a further modification. This is in many respects like the embodiment of Figures 8 and 9 but includes a pump plunger formed of drawn metal shells. That and other differences are hereinafter more fully referred to.

The attachment unit comprises a skirt 111 having an internal broken thread 112 which engages an external broken thread 113 on the neck of the bottle 114. At the top of skirt 111 is an inwardly extending flat ring portion 115 and an inwardly extending flange 116, ring and flange being in different planes. Over the bottle lip is a

compressible sealing gasket 117 of cork, pulp board or other suitable material. Held between ring 115 and gasket 117 is a supporting flange 118 for the pump barrel 119. Between flange 116

5 and flange 118 is a sealing gasket 120 of felt, rubber or other suitable material. These gaskets perform the same sealing functions, respectively, as gaskets 76, 81 of Figures 8 and 9. Gasket 120 also makes wiping contact with the pump plunger 10 to serve as a pump packing.

The cap comprises a skirt 123 telescoping over the skirt of the attachment unit, and a top portion 124 having a central opening.

15 The pump plunger is formed in two parts, both of which may be conveniently constructed in the form of drawn metal shells.

20 What may be termed the outer shell comprises a cylindrical part 125 having a running fit in the pump barrel. At the top, the outer shell has an outwardly extending flange 126 and an upwardly extending rim 127. In closed position of the cap, flange 126 engages gasket 120. At the bottom, the shell cylinder 125 has an inwardly extending bottom 128 forming the expelling head of the 25 plunger. Inside this head, the shell is dished upwardly and inwardly to form a conical valve seat 129 and then extends upwardly to form a coupling 130.

25 The inner shell comprises an upper cylindrical portion 132 and a lower cylindrical portion 133, the two being of a different diameter and joined by an annular shoulder or ledge 134. At the top, cylindrical portion 132 has an outwardly extending flange 135 which overlies rim 127 of the outer 30 shell and underlies the top of the cap.

35 The lower end of cylindrical portion 133 takes over coupling 130 with a wedging or friction fit. Wedged into upper cylindrical portion 132 with a friction fit is a headed thimble 136 having a 40 port or passage 137, the head of the thimble engaging the top of the cap. These two friction connections unite the cap and the two-part pump plunger into an operating unit.

45 Between the thimble 136 and ledge 134 is a recess 139. The interior of cylinder 133 opens into the pump barrel through coupling 130 and forms, with recess 139 and port 137, the discharge 50 passage for the container contents.

55 Located in recess 139 is a floating check valve 140 like the valve 97—98 of Figures 8 and 9.

The bottom of pump barrel 119 has an inlet port 141 for the passage of the container contents. This inlet port is controlled and the discharge passage is normally closed by a valve unit 142—143 generally like the valve unit 30—32 of Figures 1 and 2. The frusto-conical top of dome 143 seats in the valve seat 129.

60 The cap is releasably locked to the attachment unit by bayonet grooves 145 and nibs 146 like those described in connection with Figures 8 and 9. When the bayonet lock is released, the cap is moved to open position by a spring 147. Opening movement is limited and removal of the cap prevented by the engagement between an internal 65 flange 148 on the bottom of cap skirt 123 and a stop shoulder 149 formed in the skirt 111 of the attachment unit.

70 As the embodiment of Figures 10 and 11 is designed more particularly for thinner liquids, the air ports 103 of Figures 8, 9 are omitted. Except for this and except for the variation of the means for limiting opening movement, the operation of the embodiment of Figures 10 and 11 is substantially like that of the embodiment of Figures 8 and 9.

While the invention has been described in connection with a glass bottle, it is apparent that the invention is not limited to any particular kind of container.

What is claimed is:

1. In a dispensing package for liquids, and in combination, a container having a neck, an attachment unit on the container and comprising a barrel extending into the container neck and having an inlet port, a skirted cap, means for releasably locking said cap in closed position, said cap being capable of a reciprocating axial movement with respect to the container when said locking means are released, a plunger operating in said barrel, an operating connection between said plunger and the cap whereby the plunger is reciprocated upon axial reciprocation of the cap, means for limiting such axial movement, a discharge passage for expulsion of liquid by said plunger, said passage having a valve seat, and a freely floating valve element for controlling said inlet port and having a plug-like portion for engaging said valve seat to close the discharge passage when the cap is in closed position.

2. In a dispensing package for liquids, and in combination, a container having a neck, an attachment unit on the container and comprising a barrel extending into the container neck and having an inlet port, a skirted cap, means for releasably locking said cap in closed position, said cap being capable of a reciprocating axial movement with respect to the container when said locking means are released, a plunger operating in said barrel, an operating connection between said plunger and the cap whereby the plunger is reciprocated upon axial reciprocation of the cap, means for limiting such axial movement, a discharge passage for expulsion of liquid by said plunger, said passage having a valve seat, a freely floating valve element for controlling said inlet port and having a plug-like portion for engaging said valve seat to close the discharge passage when the cap is in closed position, and means for limiting the movement of said floating valve element, the range of movement of such valve element being substantially less than the range of reciprocating movement of said plunger.

3. In a dispensing package for liquids, and in combination, a container having a neck, an attachment unit on the container and comprising a barrel extending into the container neck and having an inlet port in its bottom wall, a skirted cap, means for releasably locking said cap in closed position, said cap being capable of a reciprocating axial movement with respect to the container when said locking means are released, a discharge passage for expulsion of liquid by said plunger, said passage having a valve seat, and a freely floating valve element having an annular flange-like portion normally seating on the bottom of said barrel and a plug-like central portion for engaging said valve seat to close the discharge passage when the cap is in closed position.

4. In a dispensing package for liquids, and in combination, a container having a neck, an attachment unit on the container and comprising a barrel extending into the container neck and having an inlet port in its bottom wall, a skirted cap, means for releasably locking said cap in closed position, said cap being capable of a reciprocating axial movement with respect to the container when said locking means are released, a discharge passage for expulsion of liquid by said plunger, said passage having a valve seat, a freely floating valve element having an annular flange-

like portion normally seating on the bottom of said barrel and a plug-like central portion for engaging said valve seat to close the discharge passage when the cap is in closed position, and a 5 stop element struck in from the metal of said barrel for engagement by said flange-like portion to limit movement of said floating valve element, said stop element being so positioned that the 10 range of movement of the valve element is substantially less than the range of reciprocating movement of said plunger.

5. In a dispensing package for liquids, and in combination, a container having a neck, an attachment unit on the container and comprising 15 a barrel extending into the container neck and having an inlet port, a skirted cap, means for releasably locking said cap in closed position, said cap being capable of a reciprocating axial movement with respect to the container when said locking means are released, a plunger operating 20 in said barrel, an operating connection between said plunger and the cap whereby the plunger is reciprocated upon axial reciprocation of the cap, means for limiting such axial movement, a discharge passage for expulsion of liquid by said 25 plunger, means for controlling said inlet port, means for closing said discharge passage when the cap is in closed position, and a freely floating check valve controlling said discharge passage.

30. 6. In a dispensing package for liquids, and in combination, a container having a neck, an attachment unit on the container and comprising a barrel extending into the container neck and having an inlet port, a skirted cap, means for releasably locking said cap in closed position, said 35 cap being capable of a reciprocating axial movement with respect to the container when said locking means are released, a plunger operating in said barrel, an operating connection between 40 said plunger and the cap whereby the plunger is reciprocated upon axial reciprocation of the cap, means for limiting such axial movement, a discharge passage for expulsion of liquid by said 45 plunger, means for controlling said inlet port, means for closing said discharge passage when the cap is in closed position, a floating check valve comprising a disk and a plurality of upstanding lugs, supporting means for said check valve, and stop 50 means for engagement by said lugs to limit movement of the valve.

7. In a dispensing package for liquids, and in combination, a container having a neck, an attachment unit on the container and comprising 55 a barrel extending into the container neck and having an inlet port, a skirted cap, means for releasably locking said cap in closed position, said cap being capable of a reciprocating axial movement with respect to the container when said 60 locking means are released, a plunger operating in said barrel and having an internal bore, an operating connection between said plunger and the cap whereby the plunger is reciprocated upon 65 axial reciprocation of the cap, means for limiting such axial movement, a port in the top wall of the cap communicating with the bore of said plunger and forming therewith a discharge passage, a partition located in said bore and having a port, a floating check valve normally seating on 70 said partition for controlling the port therein, means for controlling said inlet port and means for closing the discharge passage when the cap is in closed position.

8. In a dispensing package for liquids, and in 75 combination, a container having a neck, an at-

tachment unit on the container and comprising a barrel extending into the container neck and having an inlet port, a skirted cap, means for releasably locking said cap in closed position, said cap being capable of a reciprocating axial movement with respect to the container when said locking means are released, a plunger operating in said barrel and having an internal bore, an operating connection between said plunger and the cap whereby the plunger is reciprocated upon 10 axial reciprocation of the cap, means for limiting such axial movement, a port in the top wall of the cap communicating with the bore of said plunger and forming therewith a discharge passage, a cup-shaped element secured within the 15 plunger bore and having a port in its bottom wall, a floating check valve comprising a disk normally seating on the bottom of said cup-shaped element and a plurality of upstanding lugs, a stop element struck in from the wall of said cup-shaped element 20 for engagement by said lugs to limit the movement of said floating check valve, means for controlling said inlet port and means for closing the discharge passage when the cap is in closed position.

9. In a dispensing package for liquids, and in combination, a container having a neck, an attachment unit on the container and comprising a barrel extending into the container neck and having an inlet port, a skirted cap, means for releasably locking said cap in closed position, said cap being capable of a reciprocating axial movement with respect to the container when said locking means are released, a plunger operating in said barrel and having an internal bore, an operating connection between said plunger and the cap whereby the plunger is reciprocated upon 30 axial reciprocation of the cap, means for limiting such axial movement, a port in the top wall of the cap communicating with the bore of said plunger and forming therewith a discharge passage, a cup-shaped element secured within the bore of the plunger and having an opening in its bottom wall, a check valve in said cup comprising a rubber element having a central dome, said 40 dome having a slit therein, means for controlling said inlet valve, and means for closing the discharge passage when the cap is in closed position.

10. In a dispensing package for liquids, and in combination, a container having a neck, an attachment unit on the container and comprising a barrel extending into the container neck and having an inlet port, a skirted cap, means for releasably locking said cap in closed position, said cap being capable of a reciprocating axial movement with respect to the container when said locking means are released, a plunger operating in said barrel, an operating connection between said plunger and the cap whereby the plunger is reciprocated upon axial reciprocation of the cap, 50 means for limiting such axial movement, a central bore in said plunger, a discharge passage for expulsion of liquid by the plunger, including said bore, the plunger having an internal shoulder surrounding said bore, a floating check valve 55 normally seating on said shoulder to control said bore, means for limiting movement of said check valve, means for controlling said inlet port and means for closing the discharge passage when the cap is in closed position.

11. In a dispensing package for liquids, and in combination, a container having a neck, a skirted cap associated with the container neck, means whereby the cap may be releasably locked in closed position, the cap being capable of a recip- 70

- roating axial movement with respect to the container when said locking means are released, means for limiting such axial movement, a barrel extending into the container neck and having a controlled inlet port, a plunger operating in said barrel, said plunger comprising a piston-like head having a sliding fit in said barrel and a stem having a diameter smaller than that of the head, an operating connection between said plunger and the cap whereby the plunger is reciprocated upon axial reciprocation of the cap, said barrel having an opening in the wall thereof for the passage of air, a discharge passage for the expulsion of liquid by said plunger and valve means for closing said passage when the cap is in closed position.
12. In a dispensing package for liquids, and in combination, a container having a neck with a lip at the top thereof, an attachment unit comprising a skirted portion outside the container neck and a barrel suspended into the container neck, said barrel having a controlled inlet port, the container neck and the skirted portion of the attachment unit having mutually engaging screw threads, whereby the attachment unit may be secured in place on the container, a sealing gasket compressed against the container lip when the attachment unit is threaded into position, a skirted cap telescoping over said attachment unit, means whereby the cap may be releasably locked in closed position, the cap being capable of a reciprocating axial movement with respect to the container when said locking means are released, means for limiting such axial movement, a plunger operating in said barrel, said plunger comprising a piston-like head having a sliding fit in said barrel and a stem having a diameter smaller than that of the head, an operating connection between said plunger and the cap whereby the plunger is reciprocated upon axial reciprocation of the cap, said barrel having an opening in the wall thereof for the passage of air, a discharge passage for the expulsion of liquid by said plunger and valve means for closing said passage when the cap is in closed position.
13. A liquid dispensing closure for containers comprising, in combination, a threaded skirt for engagement with a thread on a container neck, whereby the skirt may be secured in place on the container, a barrel for suspension in the container neck and having a controlled inlet port, a skirted cap telescoping over said threaded skirt, interengaging means on the threaded skirt and the cap, respectively, for releasably locking the cap in closed position, the cap being capable of a reciprocating axial movement when said locking means are released, means for limiting such axial movement and preventing removal of the cap, a plunger operating in said barrel, an operating connection between said plunger and the cap whereby the plunger is reciprocated upon axial reciprocation of the cap, a discharge passage for the expulsion of liquid by said plunger and valve means for closing said passage when the cap is in locked position.
14. A liquid dispensing closure for containers, comprising, in combination, a threaded skirt for engagement with a thread on a container neck, whereby the skirt may be secured in place on the container, a barrel for suspension in the container neck and having a controlled inlet port, a skirted cap telescoping over said threaded skirt, interengaging means on the threaded skirt and the cap, respectively, for releasably locking the cap in closed position, the cap being capable of a reciprocating axial movement when said locking means are released, means for limiting such axial movement and preventing removal of the cap, a plunger operating in said barrel and having an internal bore or passage, the lower end of said bore having a valve seat, a ported and headed thimble passing through an opening in the top of the cap and engaging into the end of the plunger with a friction fit, the head of the thimble confining a portion of the cap between such head and the plunger, whereby cap, thimble and plunger are connected together as an operating unit and the plunger is reciprocated upon axial reciprocation of the cap, and a plug valve for seating in the said valve seat when the cap is in closed position, thereby to close the discharge passage through the plunger.
15. A liquid dispensing closure for containers comprising, in combination, a threaded skirt for engagement with a thread on a container neck, whereby the skirt may be secured in place on the container, a barrel for suspension in the container neck and having a controlled inlet port, a skirted cap telescoping over said threaded skirt, interengaging means on the threaded skirt and the cap, respectively, for releasably locking the cap in closed position, the cap being capable of a reciprocating axial movement when said locking means are released, means for limiting such axial movement and preventing removal of the cap, a plunger operating in said barrel and formed of a plurality of drawn metal shells, an operating connection between said plunger and the cap whereby the plunger is reciprocated upon axial reciprocation of the cap, a discharge passage for the expulsion of liquid by said plunger and valve means for closing said passage when the cap is in locked position.
16. A liquid dispensing closure for containers comprising, in combination, a threaded skirt for engagement with a thread on a container neck, whereby the skirt may be secured in place on the container, a barrel for suspension in the container neck and having a controlled inlet port, a skirted cap telescoping over said threaded skirt, interengaging means on the threaded skirt and the cap, respectively, for releasably locking the cap in closed position, the cap being capable of a reciprocating axial movement when said locking means are released, means for limiting such axial movement and preventing removal of the cap, a plunger operating in said barrel and formed of two drawn metal shells, the outer shell comprising a portion having a running fit in said barrel and an annular head at its lower end, the metal inside said head being dished upwardly and inwardly to form a frusto-conical valve seat and then upwardly to form a tubular coupling, the inner shell having a tubular lower portion fitting over said coupling with a friction fit, and a tubular portion the edge of which is engaged by the upper end of said inner shell having an outwardly turned flange engaging the top rim of the outer shell, a ported and headed thimble extending through an opening in the top of the cap and having a friction fit in the upper end of said inner plunger shell, the edge of the cap surrounding the cap opening being clamped between the head of said thimble and the top flange of the inner plunger shell, whereby cap and plunger are connected as an operating unit, and a conical plug valve for seating in said valve seat when the cap is in locked position, thereby to close the discharge passage through the plunger.
17. A liquid dispensing closure for containers

comprising, in combination, a threaded skirt for engagement with a thread on a container neck, whereby the skirt may be secured in place on the container, a barrel for suspension in the container neck and having a controlled inlet port, a skirted cap telescoping over said threaded skirt, interengaging means on the threaded skirt and the cap, respectively, for releasably locking the cap in closed position, the cap being capable of 5 a reciprocating axial movement when said locking means are released, a plunger operating in said barrel and having a piston-like end portion and a stem portion, an operating connection between said plunger and the cap whereby the plunger is 10 reciprocated upon axial reciprocation of the cap, a discharge passage for expulsion of liquid by the plunger, valve means for closing said passage when the cap is in locked position, and a stop associated with said barrel for engagement by the 15 piston-like portion of said plunger to limit the movement of the cap-plunger unit.

18. A liquid dispensing closure for containers comprising, in combination, a threaded skirt for engagement with a thread on a container neck, whereby the skirt may be secured in place on the 20 container, a barrel for suspension in the container neck and having a controlled inlet port, a skirted cap telescoping over said threaded skirt, interengaging means on the threaded skirt and the cap, respectively, for releasably locking the cap in closed position, the cap being capable of a reciprocating axial movement when said locking means 25 are released, means for limiting such axial movement and preventing removal of the cap, a plunger operating in said barrel and having an internal bore or passage, the lower end of said bore having a valve seat, a ported and headed 30 thimble passing through an opening in the top of the cap and engaging into the end of the plunger with a friction fit, the head of the thimble confining a portion of the cap between such head and the plunger, whereby cap, thimble and plunger are 35 connected together as an operating unit and the plunger is reciprocated upon axial reciprocation of the cap, a plug valve for seating in the said valve seat when the cap is in closed position, thereby to close the discharge passage through the plunger, said plunger having an internal shoulder surrounding said bore, and a floating check valve comprising a disk normally seating on said shoulder and a plurality of upstanding lugs for engaging said thimble to limit movement 40 of the check valve.

sage when the cap is in locked position, and interengaging stop elements on the threaded skirt and the cap skirt, respectively, for limiting axial movement of the plunger-cap unit.

19. A liquid dispensing closure for containers, 5 comprising, in combination, a threaded skirt for engagement with a thread on a container neck, whereby the skirt may be secured in place on the container, a barrel for suspension in the container neck and having a controlled inlet port, a skirted cap telescoping over said threaded skirt, interengaging means on the threaded skirt and the cap, respectively, for releasably locking the cap in closed position, the cap being capable of a reciprocating axial movement when said locking means 10 are released, means for limiting such axial movement and preventing removal of the cap, a plunger operating in said barrel and having an internal bore or passage, the lower end of said bore having a valve seat, a ported and headed 15 thimble passing through an opening in the top of the cap and engaging into the end of the plunger with a friction fit, the head of the thimble confining a portion of the cap between such head and the plunger, whereby cap, thimble and plunger are 20 connected together as an operating unit and the plunger is reciprocated upon axial reciprocation of the cap, a plug valve for seating in the said valve seat when the cap is in closed position, thereby to close the discharge passage through 25 the plunger, said plunger having an internal shoulder surrounding said bore, and a floating check valve comprising a disk normally seating on said shoulder and a plurality of upstanding lugs for engaging said thimble to limit movement 30 of the check valve.
